UNITED STATES PATENT OFFICE

2,572,396

SWITCH

Joseph Bailey Shockley, Detroit, Mich.

Application February 27, 1951, Serial No. 212,943

5 Claims. (Cl. 200—33)

1

This invention relates to switches, more especially for the control of lighting circuits, and has for its object to provide a simple and easily operable switch preferably of a size and model for application to existing households and similar switchboxes, my improved switch having as its main characteristic an adjustably delayed action, upon operation to break a circuit, whereby the actual break will occur at a predetermined timed interval after such operation has been effected by the user. Thus, in the case of a porch light, for instance, the user may move the switch button from the "on" to the "off" position before descending the porch steps but the circuit will not actually be broken until an interval has elapsed permitting the user to safely descend the porch steps. Other similar uses will readily be apparent.

A further object of the said invention is to provide a very simply constructed and assembled switch of the type referred to capable of being built for silent operation; and, still further, the said invention contemplates the provision of means for adjustably controlling the timing of the delayed action of the switch.

Further advantages resulting from the construction or operation of the invention as it may be carried into effect will become apparent as the same is hereinafter described, by way of example, having reference to the accompanying drawing, wherein:

Figure 1 is a rear perspective view of a switch embodying the said invention;

Figure 2 is a similar perspective view of the switch button or tumbler removed therefrom;

Figure 3 is a detail perspective view of the switch button-supporting member;

Figure 4 is a vertical cross-section of the switch button taken on a plane indicated by the line 4—4 in Figure 2;

Figure 5 is a sectional elevation, taken through the switch frame structure on a plane indicated by the line 5—5 in Figure 1, showing the switch button and its supporting member in side elevation; and

Figure 6 is a vertical longitudinal section of a slightly modified form of the switch button.

Similar characters of reference indicate similar parts in the several figures of the drawing.

10 indicates a standard type of face plate, such as is commonly used in association with household switch boxes to support the switch mechanism, and mounted on the back of this plate 10 is a switch frame structure generally numbered 11 which may be entirely of non-conducting mate-

2

rial and comprises a flat base 12 having an opening 13 therein and provided with a pair of rearwardly extending arms 14 and 15. These arms carry, respectively, contact plates 16 and 17 recessed flush into the opposed faces of the said arms 14 and 15 and each electrically connected to any suitable means, such as the screw 17, for wiring purposes in the well known manner.

Mounted as on a pivot 19, which extends between the rearmost ends of the arms 14 and 15, is a rod 20 which acts as a supporting member for a button or tumbler 21 which is provided with a bore 22 to receive the said rod 20 in a manner permitting the said button or tumbler 21 to slide coaxially over the said rod 20.

This bore 22 is reduced in diameter, as at 23, throughout a short distance from the forward end of the button 21 to provide a shoulder 24 against which one end of a compression spring 25 abuts. The opposite end of this spring 25 presses against the forward end of the rod 20, as through the medium of the set screw 26 which serves to secure an expansible washer 27 upon the forward end of the said rod 26.

Thus, the tendency of the spring 25 is to urge the button 21 forwardly on the rod 20 to a point which is limited by an enlarged abutment 28 on the rear end of the said button 21; which abutment is shown as being provided with an arcuate face 29 for a smooth wiping contact with the plate 12 of the switch frame structure 11. This enlarged rear portion of the button 21 has recessed into its opposite sides electrically connected contact fingers 30 and 31 for the purpose of closing an electrical circuit between the contact plates 16 and 17 in all positions of movement of the switch button 21 other than the lower and forward "off" position of the said button as will become apparent.

It will be seen that the contact plate 16 is notched on its lower edge at 16' and similarly (although not necessarily) the plate 17 as shown as notched at 17' so that, when the button 21 is raised to the "on" position shown in full lines in Figure 5, the contact fingers 30 and 31 will bridge the contact plates 16 and 17 regardless of what position of adjustment along the rod 20 the said switch button may occupy.

However, when the switch button is depressed to the "off" position, as shown in broken lines in the said Figure 5, the said contact fingers 30 and 31 will only bridge the plates 16 and 17 when the button is pushed rearwardly of the device over its supporting rod 20 as, when the button is otherwise in its forward and depressed "off" posi-

tion, as also shown in broken lines in the said Figure 5, the contact fingers 30 and 31 will not impinge the said contact plates but instead will register with the notches 16' and 17' thereof.

Thus, in the forward position of the switch button, it may immediately close and open the circuit through the plates 16 and 17 as it is raised and lowered; but, if the button 21 is first moved rearwardly over its supporting shaft 20, the circuit will remain closed regardless of whether the button occupies a depressed or "off" position until such time as the action of the spring 25 automatically returns the button to its normal forward operating position.

The speed of this automatic forward movement of the switch button is intended to be damped or regulated by a suitable brake, which may simply be a distortable washer 27 such as of rubber-like material subject to adjustable compression by a set screw 26. The effective diameter of this brake member 27 may be increased by adjusting the set screw toward the rod 26 and decreased by the reverse adjustment, as will be obvious, and such adjustment will, therefore, regulate the peripheral pressure of the member 27 on the wall of the bore 22 whereby such regulated braking action, or friction, between the said member 27 and the wall of the bore 22 will operate to time the reflex action of the spring 25 after the switch button 21 has been pushed rearwardly on its supporting rod 20. The reduced orifice 23 in the forward end of the button 21 admits of the passage of a small screw driver therethrough to effect adjustments of the set screw 26.

In operation, the described switch mechanism may be utilized to merely close and open a circuit as the switch button (in its forward position on the rod 20) is raised and lowered, but, should a delayed action be desired, the switch button 21 is simply pushed rearwardly on its rod 20 so that the resulting short-radius arcuate movement of the contact fingers 30 and 31 is rearward of the notches 16' and 17' of the contact plates. Under these conditions, when the button in such rearward position is depressed to the "off" position, the electrical circuit between the contact plates will remain closed until such time as the button 21, under the partially restrained action of the compression spring 25, is returned to its forward position and so causes the contact fingers 30 and 31 to move into the area of the recesses 16' and 17' thereby automatically breaking the circuit.

The time elapsing, between the depressing of the rearwardly set contact button to its lower "off" position and the full movement thereafter of the button to its forward contact-breaking position by the action of the spring 25, is determined by the amount of braking resistance set up between the washer 27 and the wall of the bore 22 by the described adjustment.

The slight modification shown in Figure 6 is simply to indicate that the return movement of the switch button on its shaft may not necessarily be of a uniform speed throughout but may be accelerated, after the desired delayed action has been accomplished, in order to secure a more instantaneous breaking of the circuit should this be desired. With the form of structure described, this effect may be simply secured by enlarging a portion of the bore 22 of the button 21, as at 22', in the form of a counter bore whereby braking pressure between the wall of the bore 22 and the brake member 27 will be relieved during the final

portion of the forward movement of the button 21 on its rod 20, as will be obvious.

What I claim is:

1. In a delayed action switch, a frame structure, a pivot, a tumbler arm pivoted thereon for swingable movement to "off" and "on" positions, a tumbler manually slidable on said arm toward said pivot, a conductor carried by said tumbler, a pair of spaced contacts positioned for circuit-closing by said conductor when said tumbler is swung to its "on" position, a pair of contacts positioned to close a circuit through said conductor when swung to both its "on" and "off" positions when said tumbler is moved toward said pivot, and biasing means for returning said tumbler to its forward position removed from said pivot following its manual rearward movement towards said pivot.
2. In a delayed action switch, a frame structure, a pivot, a tumbler arm pivoted thereon for swingable movement to "off" and "on" positions, a tumbler manually slidable on said arm toward said pivot, a conductor carried by said tumbler, a pair of spaced contacts positioned for circuit-closing by said conductor when said tumbler is swung to its "on" position, a pair of contacts positioned to close a circuit through said conductor when swung to both its "on" and "off" positions when said tumbler is moved toward said pivot, and biasing means for returning said tumbler to its forward position removed from said pivot following its manual rearward movement towards said pivot.
3. In a delayed action switch, a frame structure, a pivot, a tumbler arm pivoted thereon for swingable movement to "off" and "on" positions, a tumbler manually slidable on said arm toward said pivot, a conductor carried by said tumbler, a pair of spaced contacts positioned for circuit-closing by said conductor when said tumbler is swung to its "on" position a pair of contacts positioned to close a circuit through said conductor when swung to both its "on" and "off" positions when said tumbler is moved toward said pivot, and timed biasing means for returning said tumbler to its forward position removed from said pivot following its manual rearward movement towards said pivot.
4. In a delayed action switch, a frame structure, a pivot, a tumbler arm pivoted thereon for swingable movement to "off" and "on" positions, a tumbler manually slidable on said arm toward said pivot, a conductor carried by said tumbler, a pair of spaced contacts positioned for circuit-closing by said conductor when said tumbler is swung to its "on" position a pair of contacts positioned to close a circuit through said conductor when swung to both its "on" and "off" positions when said tumbler is moved toward said pivot, biasing means for returning said tumbler to its forward position removed from said pivot following its manual rearward movement towards said pivot, and an adjustable brake yieldably resisting such forward movement of said tumbler to a degree determined by its adjustment.
5. In a delayed action switch, a frame structure, a pivot, a tumbler arm pivoted thereon for swingable movement to "off" and "on" positions, a tumbler manually slidable on said arm toward said pivot, a conductor carried by said tumbler, a pair of spaced contacts positioned for circuit-closing by said conductor when said tumbler is swung to its "on" position a pair of contacts

positioned to close a circuit through said conductor when swung to both its "on" and "off" positions when said tumbler is moved toward said pivot, biasing means for returning said tumbler to its forward position removed from said pivot following its manual rearward movement towards said pivot, a brake frictionally disposed between said arm and said tumbler to yieldably resist forward movement of said tumbler, and means for adjusting the effective pressure of said brake.
